UNITED STATES PATENT OFFICE.

BEN BERKOWITZ, OF NEW YORK, N. Y.

DESIGN FOR A COMBINED MENU AND MATCH-BOX HOLDER.

Application filed September 17, 1926. Serial No. 19,105. Term of patent 3½ years.

To all whom it may concern:

Be it known that I, BEN BERKOWITZ, a citizen of the United States, and a resident of New York city, borough of Bronx, in the county of the Bronx, State of New York, United States of America, have invented a new, original, and ornamental Design for a Combined Menu and Match-Box Holder, of which the following is a specification, reference being had to the accompanying drawing, forming part thereof.

I claim:

The ornamental design for a combined menu and match-box holder, substantially as shown.

BEN BERKOWITZ.
